ABSTRACT OF THE DISCLOSURE

A battery of coke ovens comprises a plurality of horizontal coke ovens with hollow firing members on both sides of the ovens; the hollow members are connected to regenerators which in turn are connected to longitudinal side flues at the feed and discharge sides of the battery. The side flues empty into respective transverse channels at the center of the battery, which channels lie side-by-side and exhaust into a common stack.

The present invention relates to batteries of horizontal coke ovens, and more particularly to improvements relating to smoke-exhausting flues.

The existing batteries of coke ovens comprise a plurality of horizontal coke ovens with firing hollow members located on both sides thereof, said hollow members being provided with vertical channels, in which gaseous fuel is burnt to heat the coke ovens. The products of combustion or flue gases are directed through regenerators, located below the coke ovens, from the vertical channels into side flues that are disposed on the coke-pusher and coke discharge sides along the entire battery of coke ovens. The side flues are connected to a collecting transverse flue at the end side of the battery, said transverse flue being intended for directing flue gases into the stack. The cross sections of the flues are selected depending upon the maximum rate of flow combustion products, which occurs, as is well known, at the outlet end of the flues, and upon the minimum resistance offered to the products of combustion during their flow.

When constructing batteries of coke ovens composed of a large number of high-capacity coke ovens, the amount of products of combustion to be exhausted increases considerably. In this case, it is necessary to construct smoke-exhausting flues of large cross sections, which results in increased construction work when erecting flues and foundations of a coke-oven battery and hence in their higher cost.

At the same time, it proves to be very difficult to maintain and control the draft in the flues over the length of the battery.

An object of the invention is to eliminate the above-said difficulties.

It is proposed to construct a battery of coke ovens provided with smoke-exhausting flues without any considerable increase in their cross sections, said flues ensuring a steady control and maintenance of the draft of combustion products over the entire length of the coke-oven battery.

The present invention envisages a horizontal battery of coke ovens composed of a plurality of coke ovens, each oven having on both sides firing hollow members provided with vertical firing channels, communicating through regenerators with lateral smoke-exhausting flues located along the coke discharge and coke-pusher sides of said

2

coke-oven battery and connected to a collecting smoke-exhausting flue leading to the stack. In conformity with the invention, the collecting flue is composed of two channels disposed in the middle section of the battery; one of the channels being connected to the side flues on the coke sides of the battery, while the other is connected to flues disposed on the coke-pusher side of this coke-oven battery.

An essential advantage of the present invention is that the amount of products of combustion flowing through the side flues at the place of their junction with the collecting flue of this side is half that observed with the conventional arrangement of the collecting flue in the end side of the coke-oven battery. This provides for a considerable decrease in the size of the flues and, hence, in the height of foundations, with the former rates of flow of combustion products in the flues being preserved.

The details of the present invention will become more fully apparent from a consideration of the following description of an exemplary embodiment thereof, taken in conjunction with the accompanying drawings, wherein:

FIG. 1 diagrammatically represents a battery of coke ovens according to the invention, shown in longitudinal section;

FIG. 2 is a cross-sectional view taken on line A—A of FIG. 1;

FIG. 3 is a cross-sectional view taken on line B—B of FIG. 2.

The battery of coke ovens is composed of a plurality of horizontal coke ovens 1 (FIGS. 1 and 2) with hollow members 2 disposed on both sides thereof. These hollow members 2 are provided with vertical firing channels 4 divided by partitions 3, and the products of combustion are supplied through oblique passages 5 into regenerators 6, said regenerators being essentially chambers with a checkerwork of refractory brick and located under the ovens 1 and hollow members 2. From the regenerators 6 the products of combustion are supplied through bottom flues 7 via valves (not shown in the drawing) and flue branch pipes 8 into side flues 9 and 10 (FIGS. 2 and 3), located respectively along the coke-pusher and coke discharge sides of the battery inside or outside its foundation 11.

The side flues 9 on the coke-pusher side of the coke-oven battery emerge into a channel 12 of the collecting flue, while the side flues 10 on the coke discharge side of the battery emerge into a channel 13 of the collecting flue. The channels 12 and 13, as shown in FIGS. 1 to 3, are disposed in the middle section of the battery perpendicular to said flues 9 and 10; and are united into a common collecting flue at the stack.

When drawing off the products of combustion from the central part of the battery, separately on its coke-pusher and coke discharge sides, the amount of products of combustion in the side flues 9 and 10 in the section before the channels 12 and 13 will be half as that in the case of the conventional arrangement of the collecting flue at the end side of the battery. This fact allows, with the same rate of flow of combustion products, a considerable decrease in the cross section of the flues 9 and 10 and in the total height of the foundation 11 of the coke-oven battery.

Since the length of the side flues 9 and 10 up to their transition into the collecting channels 12 and 13 is reduced in half, favorable conditions arise for controlling the draft over the length of the coke-oven battery by having recourse to conventional control devices.

The application of the present invention allows a reduction in the cost of coke-oven batteries and improves the conditions of heating coke ovens.

The invention is not limited by the embodiment thus described, and there may be modifications thereof without departing from the concept and scope of the invention.

What is claimed is:

1. A battery of coke ovens comprising a plurality of horizontal coke ovens having discharge and pusher sides; firing hollow members arranged on both sides of said coke ovens and provided with vertical channels; side smoke-exhausting flues located along the coke-discharge and coke-pusher sides of said coke-oven battery; regenerators connecting said hollow members to said side flues; a collecting smoke-exhausting flue provided with two channels each located centrally of said coke-oven battery and extending transversely of said side flues, one of said channels being connected to said side flues on the coke-discharge side of the coke-oven battery, and the other channel to said side flues disposed on the coke-pusher side of said coke-oven battery; and a stack connected to said smoke-exhausting flue.

2. A battery of coke ovens as claimed in claim 1 com-

prising a foundation supporting said ovens, said hollow members, said side flues and said regenerators, said collecting flue being in said foundation.

3. A battery of coke ovens as claimed in claim 1 wherein in said side flues extend longitudinally along said battery.
